UNITED STATES PATENT OFFICE.

WENZEL ENGLICH, OF ST. LOUIS, MISSOURI.

KNOCKDOWN SHIPPING-CRATE.

No. 926,931.

Specification of Letters Patent.

Patented July 6, 1909.

Application filed October 19, 1908. Serial No. 458,388.

To all whom it may concern:

Be it known that I, WENZEL ENGLICH, a citizen of the United States, and resident of St. Louis, Missouri, have invented certain new and useful Improvements in Knockdown Shipping-Crates, of which the following is a specification.

My invention relates to improvements in knockdown shipping crates, which consists 10 in the provision of folding sides and ends so arranged that the entire crate can be folded and reconveyed to the shipper.

The object of my invention is to construct a shipping crate, its sides and ends hinged to 15 the bottom, the top member hinged to the ends, and provided with fastening devices by which the same is held in rigid position when in crate form, the several parts forming the crate arranged to be folded so that it can 20 be reconveyed to the shipper in compact form.

In the drawings—Figure 1 is a perspective view of my complete invention. Fig. 2 is an end view of the same when in a folded position. Fig. 3 is a sectional view taken on the 25 line 3—3 of Fig. 1. Fig. 4 is a detail view of the locking pin made use of in securing the top to the side walls. Fig. 5 is a detail enlarged view of a portion of the bottom and 30 side, showing the double hinge made use of.

In the construction of my invention I provide a bottom 6, two end sections 7 and 8, two side sections 9 and 10 and a top 11. To the bottom 6 is secured the sides 9 by means 35 of double swing hinges 12 which is for the purpose of permitting the side sections 9 to be laid inwardly as shown by light dotted lines in Fig. 3, or outwardly as shown by heavy dotted lines (see Fig. 3), this position 40 being adaptable for cleaning the interior and bottom of the crate. The end section 8 is hinged to a strip 13 attached to the bottom 6, the opposite end 7 hinged to a narrower strip 14. The object of these strips is to permit the end section 7 to fold downwardly on 45 the end section 8.

To the upper ends of the end sections 7 and 8 is hinged the top 11 so arranged that when folded will assume the position as shown in 50 Fig. 2. The side sections 9 and 10 are pro-

vided at the upper edge with sockets 15 through which are passed the pins 16, said pins first passing through the opening 17 formed in the top, the said locking pins have projections 18 formed on the bottom ends and a 55 collar 19 at the top. When the said pins are inserted through the openings 17 and the sockets 15, the projections 18 by means of the slit 20 formed in the pin will spread outwardly and contact with the under surface 60 of the sockets, locking the same. The pins are attached to the top by a chain or the like 21, so they will not become disconnected from the crate and lost. The bottom 6 is provided with openings 22 in which are 65 placed sleeves, the same being in such position as to be in direct alinement with the openings 17 formed in the top when the same is in folded position, so that the said pins or a set of the same may be passed 70 through the openings 22 and lock the crate through the openings 22 and lock the crate in a folded position. The top 11 is provided with a door 23 through which the fowl may be removed from the crate and said door is 75 provided with a latch 24 by which it is locked.

This crate is especially designed for the purpose of shipping fowl and when empty can be folded by first removing the pins 16, folding the side walls 9 and 10 inwardly as shown 80 by light dotted lines in Fig. 3, then collapsing the remainder of the crate as shown in Fig. 2. The set of pins 16 is then inserted through the openings in the bottom and the 85 crate is ready to be reconveyed back to the shipper. In this manner a number of folded crates can be used in the same amount of space which the crate when in an extended position would occupy.

Having fully described my invention what 90 I claim is:

In a knockdown shipping crate, the combination with a suitable solid bottom of a pair of side sections formed of strips hingedly secured to said solid bottom by two-way 95 hinges, of a pair of end sections formed of strips hingedly mounted to the bottom and arranged to swing in the same direction; a top formed of strips hingedly connected to the end sections; a solid door located in a 100

solid portion formed in the top; a pair of split locking pins arranged to pass through the top and engage in sockets formed on the side sections so as to lock the crate in an upright position and to register with an opening formed in the bottom so as to hold the crate in a locked position when folded, substantially as specified.

In testimony whereof, I have signed my name to this specification, in presence of two 10 subscribing witnesses.

WENZEL ENGLICH.
